GAME BOARD

Rodney L. Smith, 1200 Garland St.,
Pampa, Tex. 79065

Filed July 29, 1974, Ser. No. 492,888

Term of patent 14 years

Int. Cl. D21—01

U.S. Cl. D34—5 SS

FIG. 3

FIG. 1 is a top perspective view of a game board according to my new design, which view is, also, the view as generally seen along direction of arrow 1A shown in FIGS. 2 and 4.

FIG. 2 is a top plan view of the design of the game board shown in FIG. 1.

FIG. 3 is one side view of the design of game board shown in FIG. 1 and is, also, the view thereof as seen along direction of arrow 3A of FIG. 2.

FIG. 4 is another side view of the design of game board shown in FIG. 1 and is, also, the view thereof seen along direction of arrow 4A of FIG. 2.

FIG. 4

The objects on the platforms are an integral affixed part thereof.

I claim:

The ornamental design for game board, as shown and described.
